UNITED STATES PATENT OFFICE.

EMANUEL AUFIERO AND MICHAEL A. AUFIERO, OF BROOKLYN, NEW YORK.

DESIGN FOR A WARNING-SIGNAL CASING AND TERMINALS.

43,952.

Specification for Design.

Patented Apr. 29, 1913.

Application filed May 27, 1912. Serial No. 700,119. Term of patent 7 years.

To all whom it may concern:

Be it known that we, EMANUEL AUFIERO and MICHAEL A. AUFIERO, citizens of the United States, residing at Brooklyn, in the county of Kings and State of New York, have invented a new, original, and ornamental Design for a Warning-Signal Casing and Terminals, of which the following is a specification, reference being had to the accompanying drawing, forming part thereof.

Figure 1, is a side elevation showing the

design of the article; Fig. 2 is a rear view showing arrangement of terminals and wiring.

We claim:

The ornamental design for a warning signal casing and terminals as shown.

EMANUEL AUFIERO.
MICHAEL A. AUFIERO.
